CLOCK

Filed Sept. 24, 1935

UNITED STATES PATENT OFFICE

2,101,235

CLOCK

Gordon Miller Buehrig, Auburn, Ind., assignor to
 Auburn Automobile Company, Auburn, Ind., a
 corporation of Indiana

Application September 24, 1935, Serial No. 41,888

5 Claims. (Cl. 58—50)

The present invention relates generally to clocks. More particularly the invention relates to that type of clock which is designed to be mounted on the dashboard of a vehicle such as 5 an automobile and is adapted to have the dial thereof illuminated by an electric light on the dashboard.

One object of the invention is to provide a 10 clock of this type which may be read more readily than previously designed clocks of like character, by reason of the fact that the hour scale is separate from, and is disposed inwardly of, the minute scale.

Another object of the invention is to provide 15 a clock of the type under consideration in which the hour and minute hands are disposed behind the hour and minute scales and the latter are illuminated in a novel and efficient manner so as to permit of ready reading of the clock at 20 night.

A further object of the invention is to provide 25 a clock which is generally of new and improved construction and may be manufactured at a low and reasonable cost.

Other objects of the invention and the various 30 advantages and characteristics of the present clock construction will be apparent from a consideration of the following detailed description.

The invention consists in the several novel 35 features which are hereinafter set forth and are more particularly defined by claims at the conclusion hereof.

In the drawing which accompanies and forms 40 a part of this specification or disclosure and in which like numerals of reference denote corresponding parts throughout the several views:

Figure 1 is a front or face view of a clock embodying the invention;

Figure 2 is a face view of one of the glass discs 45 which form or comprise the dial of the clock;

Figure 3 is a fragmentary face view of the 50 clock, the bezel, crystal and outer glass disc of the dial being omitted for purposes of illustration;

Figure 4 is a view of the clock partly in section and partly in side elevation; and

Figures 5 and 5^a are enlarged sectional views taken respectively on the lines 5—5 and 5^a—5^a of Figure 1.

The clock which forms the subject matter of the invention is designed to be mounted on the dashboard of a vehicle such, for example, as an automobile. It is adapted, as hereinafter described, to be illuminated by one of the electric 55 lights on the dashboard and comprises, as the

main or essential parts thereof, a casing 5, a ring 6, a dial 7, a crystal 8 and a bezel 9.

The casing 5 is formed of sheet metal and consists of an inner section 10 and an outer section 11. The inner section 10 is cylindrical and serves as a housing for the operating parts of the clock. These parts form no part of the invention and, therefore, do not appear in the drawing. If desired, they may be electrically operated and supplied with current by way of a conductor 12 leading from the battery of the automobile to a binding post 13 at the rear end of the casing section 10. The outer section 11 of the clock casing is affixed to the inner section 10 and consists of a sleeve-like part 14, a flat ring-shaped 15 wall 15, and a cylindrical side wall 16. The sleeve-like part 14, as shown in Figure 4 of the drawing, surrounds the front end of the casing section 10. It is riveted, pinned, soldered, or otherwise fixedly secured to the inner casing section 10, and serves as a medium whereby the two sections of the casing are fixedly secured together. The ring-shaped wall 15 is formed integrally with, and extends radially from, the outer end of the sleeve-like part 14, and is joined to the inner end of the cylindrical side wall 16. The latter has an integrally outturned flange 17 at its outer end and forms, with a disc 18 and the ring 6, a compartment 19 for an hour-hand 20 and a minute-hand 21. The disc 18 is slightly smaller in diameter than the internal diameter of the side wall 16 and is secured against the outer face of the ring-shaped wall 15 of the outer casing section 11. It serves as a closure for the outer or front end of the inner casing section 10 and is imperforate, except for a small hole 22 in the central portion thereof. The hour-hand 20 is fixedly secured to and extends radially from the outer end of a horizontally extending sleeve 23. This sleeve extends through the hole 22 in the disc 18 and, as well understood in the art, is driven or rotated by the operating parts of the clock so that it swings the hand 20 360° during each twelve-hour period. The minute-hand 21 is disposed directly in front of the hour-hand and is secured to and extends radially from a shaft which extends through the sleeve 23 and is connected to, and driven by, the operating parts of the clock, so that it swings the minute-hand 21 360° every hour. The hour- and minute-hands are disposed in close proximity to the outer face of the disc 18 and are adapted to be adjusted or set by means of a shaft 24 which extends through the back of the 55

inner casing section 10 and has a knurled knob 25 whereby it may be turned manually.

The ring 6 is substantially the same in internal and external diameter as the ring-shaped wall 15 5 of the outer casing section 11. It is formed of sheet metal and embodies at the outer margin thereof an outwardly extending cylindrical flange 26 and an outturned ring-shaped flange 27. The cylindrical flange is formed integrally with the ring 10 and serves, as hereinafter described, as a seat for the dial 7. The outturned flange 27 fits against the outturned flange 17 of the outer casing section 11 and is clamped against said last 15 mentioned flange by means of the bezel 9. The ring 6 is spaced from the disc 18 and permits the hour- and minute-hands in the compartment 19 to be readily viewed. Light from the electric 20 light on the dashboard of the automobile on which the clock is mounted, is permitted, through the medium of a pair of windows 28, to pass into the compartment 19 so as to illuminate the hands 29 and 21. The windows, as shown in the drawing, are in the form of arcuate slots in the cylindrical side wall 16 of the outer casing section 11. 25 They are positioned, one substantially diametrically opposite the other, and have strips 29 of translucent celluloid thereover, in order that the light passing therethrough is diffused and is equally distributed in the compartment 19. The celluloid strips 29 extend around the side wall 16 30 of the outer casing section 11 and are fixedly secured in place by means of studs or rivets 30 which pass through the ends thereof and are anchored or secured to the portions of the side wall 16 35 which define the ends of the window-forming slots. As shown in the drawing, the minute-hand 21 is, as far as length is concerned, equal to the radius of the inner edge of the ring 6 and the hour-hand 20 is approximately one-half as long 40 as the minute-hand.

The dial 7 consists of a pair of glass discs 31 and 32 and has an hour scale 33 and a minute scale 34. The disc 31 fits against the outer face of the ring 6 and is held against movement in the plane 45 thereof by means of the flange 26 on the ring. The disc 32 is the same in diameter as the disc 31. It is held in place by the flange 26 and is spaced slightly outwardly from the disc 31 by means of a washer-like element 35. The latter 50 fits between the outer margins of the two discs and is concealed, as shown in Figure 5, by the bezel 9.

The hour scale 33 coacts with the hour-hand 20 to indicate the hour and consists of an annular series of hour indicating numerals 36. This series is concentrically positioned with respect to the sleeve 23 for swinging the hour-hand, and the numerals 36 thereof are painted or otherwise marked on the inner face of the glass disc 32. 55 As shown in Figure 1, the numerals 36 are disposed on the disc 32 at a point midway between the center of the disc and the inner edge of the ring 6. In order to form a background for the numerals, a circular, opaque stripe 37 is formed by painting, or in any other suitable manner, on the front face of the glass disc 31. This stripe is 60 preferably of a different color from the numerals so that the latter stand out clearly. The portions of the discs 31 and 32 enclosed by the opaque stripe 37 are transparent so that the hour-hand 20 is readily visible. In order to permit the hour numerals to be illuminated by the beams of light emanating from the lamp on the dashboard on which the clock is mounted, a pair of 65 cut-outs 38 are formed in the flanges 26 and 27

of the ring 6 at points adjacent the windows 28. These cut-outs permit beams of light from the dashboard lamp to pass in front of the ring and through the glass disc 32, so as to illuminate the hour-indicating numerals 36. By having the hour-hand 20 illuminated by light passing behind the ring and by having the hour-indicating numerals 36 illuminated by light passing in front of the ring, the hand and the numerals are illuminated in a novel manner and in such a way that they may be readily seen.

The minute scale 34 coacts with the minute-hand 21 to show the minutes past the hour and consists of an annular series of lines or graduations 39 and an annular series of numerals 40. 15 The graduations 39 are painted or marked in any suitable manner on the inner or rear face of the glass disc 31 and are positioned so that they radiate outwardly from a circle which coincides with the inner edge of the ring 6. As shown in Figures 20 1 and 3, the graduations 39 are sixty in number and each fifth graduation is longer than the others so as to indicate five-minute intervals. The numerals 40 are painted or otherwise formed on the inner face of the glass disc 32. They are 25 associated respectively with, and are located outwardly of, the long graduations 39 to indicate or designate five-minute intervals. By reason of the fact that the graduations 39 are formed on the inner face of the glass disc 31, and the numerals 30 40 are formed on the inner face of the glass disc 32, the numerals are spaced forwardly of the graduations and, as a result of the illumination resulting from the passage of light through the cut-outs 38, appear to be raised with respect to 35 the graduations. By having the hour scale separate from and disposed within the minute scale, the clock may be read more readily than clocks wherein the hour and minute scales coincide. To prevent relative rotation of the discs 32 and 31, 40 an inwardly extending lug 41 is formed on the flange 26 of the ring 6. This lug, as shown in Figure 3, fits within notches 42 on the outer margins of the glass discs.

The bezel 9 is ring-shaped and is disposed in front of, and in concentric relation with respect to, the side wall 16 of the outer casing section 11. The inner margin of the bezel is shaped to form an internal seat 43 and an inwardly facing groove 44. The crystal 8 of the clock is disposed 45 in front of the glass disc 32 of the dial and has the margin thereof seated in the seat 43, as shown in Figure 5. A cork ring or gasket 45 is disposed in the groove 44 and serves to press the margin of the crystal 8 against a ring-shaped 50 gasket 46. The inner portion of this gasket fits between the outer margins of the crystal and the glass disc 32 and the outer portion of the gasket fits, and is clamped between the bezel 9 and the outturned flange 27 of the ring 6. The outer margin of the bezel is bent inwardly to 55 form an annular flange 47 which encircles the outturned flanges 27 and 17 and serves to hold, in clamped relation, the bezel 9, ring 6 and outer casing section 11, as well as the crystal 8 and the glass discs 31 and 32. In order to secure the clock in place on the dashboard of the automobile with which it is associated, the bezel is provided with diametrically opposite ears 48. These ears have apertures 49 extending therethrough 60 for bolts or other attaching devices and are arranged in registry with a pair of diametrically opposite ears 50 on the out-turned flange 17 of the side wall 16 of the outer section 11.

The clock may be readily read in day time be- 75

cause of the fact that the hour scale is positioned within the minute scale. In addition, the clock may be read readily at night because of the specific manner in which the hour- and minute-hands and the hour and minute scales are illuminated. Because of the comparatively small number of parts and the manner in which the hour and minute scales are formed on the dial 7, the clock, as far as the casing and the parts 10 hereinbefore described are concerned, may be manufactured at a low and reasonable cost.

Whereas the clock has been described as being electrically operated, it is to be understood that it may be spring-driven or actuated. It is also 15 to be understood that the invention is not restricted to the details set forth, since these may be modified within the scope of the appended claims, without departing from the spirit and scope of the invention.

Having thus described the invention, what I 20 claim as new and desire to secure by Letters Patent is:

1. A clock comprising in combination, a casing for clock-operating mechanism, a dial in the 25 front portion of the casing comprising a pair of transparent plates arranged one in front of the other, said dial having around the outer portion thereof, a minute scale in the form of a circular series of minute graduations on the inner plate 30 and numerals formed on the outer plate around the graduations and adapted to indicate five-minute intervals and also having an inner scale within the outer scale in the form of an annular series of hour-indicating numerals on one of the 35 plates, and minute- and hour-hands disposed within the casing and coacting respectively with the minute and hour scales on the dial.

2. A clock comprising in combination, a casing for clock-operating mechanism, a dial disposed 40 in the front portion of the casing and comprising a pair of glass plates disposed one in front of the other, said dial having around the outer portion thereof a minute scale in the form of a circular series of minute graduations on the inner 45 face of the inner plate and a circular series of numerals on the other plate and around the graduations for indicating five-minute intervals and also having an hour scale within the minute scale in the form of an annular series of hour- 50 indicating numerals on the outer plate, and minute- and hour-hands disposed in the casing behind the dial and coacting respectively with said minute and hour scales.

3. A clock comprising in combination, an open 55 front casing having clock-operating mechanism

in the rear portion thereof and provided with an opaque plate in front of the mechanism and spaced inwardly from the front thereof, an opaque ring mounted in the casing in front of the plate, a transparent dial disposed in front 5 of the ring and having a scale consisting of an annular series of graduations adjacent to the inner edge of the ring, minute- and hour-hands positioned in the casing between the plate and the ring and connected for movement by the 10 mechanism, and windows in the casing for admitting light into the space between said ring and plate for dial illuminating purposes.

4. A clock comprising in combination, an open front casing having clock-operating mechanism 15 in the rear portion thereof and provided with an opaque plate in front of the mechanism and spaced inwardly from the front thereof, an opaque ring mounted in the casing in front of the plate, a transparent dial disposed in front of 20 the ring and having around the outer portion thereof and adjacent to the inner edge of the ring, a minute scale and also having a separate hour scale within the minute scale, minute- and 25 hour-hands positioned between the plate and ring and connected for movement by the mechanism, and window means in the casing for admitting light into the space between said plate and ring for dial illuminating purposes.

5. A clock comprising in combination, an open front casing having clock-operating mechanism 30 in the rear portion thereof and provided with an opaque plate in front of the mechanism and spaced inwardly from the front portion thereof, an opaque ring mounted in the casing in front 35 of the plate, a dial disposed in front of the ring and comprising a pair of glass plates disposed one in front of the other, said dial having around the outer portion thereof and adjacent to the inner edge of the ring, a minute scale in the form of a circular series of minute graduations on the inner glass plate and a circular series of numerals on 40 the outer plate and around the graduations for indicating five-minute intervals, and also having an hour scale within the minute scale in the form of an annular series of hour-indicating numerals 45 on the outer plate, minute- and hour-hands disposed in the casing between the ring and the opaque plate and connected for movement by the mechanism, and windows in the front portion of the casing for admitting light into the space between said ring and opaque plate, and also in 50 front of the ring.

GORDON MILLER BUEHRIG.
